UNITED STATES PATENT OFFICE.

JOSEPH LESQUENDIEU, OF PARIS, FRANCE, ASSIGNOR TO J. LESQUENDIEU INC., OF NEW YORK, N. Y., A CORPORATION OF NEW YORK.

BOX FOR SALVE OR CREAM.

Application filed January 4, 1927, Serial No. 158,967, and in France August 18, 1926.

In the co-pending application Serial No. 158,966 filed January 4, 1927, in the name of the present applicant for improved box for salve or cream, there is described a box or tube more particularly adapted to contain salve or cream, and consisting in the combination of a body having a plug movable therein and provided with a cup, and a stopper adapted to be coated. 5 The plug is advanced in proportion to the use of the salve which it contains so as to bring this material always in contact with the projection on the stopper.

The present invention has for its object to convert this tube so as to enable the salve in stick form to be used directly without the intermediary of the stopper.

In the accompanying drawing a section of a tube for this purpose is illustrated.

20 The body 1 is provided with a central tubular space 2 and an internal screw thread 3. At its upper end however the screw threaded portion 4 is on the outside for the reception of a cap 8 which may be as long 25 as may be desired.

A movable plug 5 is screwed into the internal screw thread 3 and the movement thereof may be readily effected by means of the groove or kerf 7.

30 The stick of salve 6 is engaged within the cup of the plug 5.

It will be readily understood that as the stick 6 is used by direct application it is sufficient to give a few turns to the plug 5, which 35 is effected by means of a finger nail as the movement is easy, so as to cause the stick to rise and enable it to be used until the plug 5 has been screwed completely into the body 1. Similarly it will be noted that as the 40 plug 5 is rotated in the other direction it will be retracted in the tubular member and will consequently retract the stick 6 carried thereby. As in the case of the co-pending application above referred to no precaution 45 is necessary to prevent the fingers from coming into contact with the stick of salve at any time.

From the drawing it will be apparent that the lowermost plane surface of the plug 5 50 forms a perfectly flat base on which the

whole box carrying the lipstick may be placed, the plug itself forming the base when retracted beyond the end of the tubular member. When the plug has been advanced sufficiently so as to be completely 55 housed within the tubular member then the circular end of the tubular member 1 itself forms the circular base of the box. It will thus be seen that irrespective of the position of the plug 5, there always will be a flat 60 stable base for the whole device.

It will be further noted that due to the fact that the stick 6 has a much smaller diameter than the internal diameter of the threaded portion 3, the material of said stick 65 can never under any circumstances come into contact with or touch the internal threads 3, so that such threads never become fouled.

Having thus described my invention what 70 I claim as new and desire to secure by Letters Patent is:—

1. A box of the character described comprising a tubular member having an internal screw thread at one end extending a substantial distance therein and a short external thread at the other end, a screw cap adapted to be screwed on the external thread of said tubular member, and a short carrier plug screwing into the internal thread of said tubular member and capable of being completely housed within said tubular member, said plug at its inner end having a stick of salve fitted therein and having its outer end formed as a plane surface perpendicular to 75 the vertical axis of the box, whereby said box may be placed upright irrespective of the position of the plug, and a kerf provided on the plane surface of the plug for facilitating rotation thereof to advance and retract the plug and stick of salve carried thereby.

2. A box of the character described comprising a tubular member having an internal screw thread at one end extending a substantial distance therein and a short external screw thread at the other end, a screw cap adapted to be screwed on the external thread of said tubular member, and a short carrier plug screwing into the internal 80 85 90 95 100

thread of said tubular member and capable of being completely housed within said tubular member, said plug at one end having a stick of salve fitted therein which is of less diameter than the internal diameter of the internal thread so as to prevent the material of the stick fouling the internal thread and said

plug having its other end formed as a flat surface with a kerf, whereby the flat surface of the plug acts as a stable base for the box 10 and the kerf facilitates rotation of the plug to advance and retract the stick carried thereby.

JOSEPH LESQUENDIEU.
